(57) CLAIM

The ornamental design for a video camera housing for a football helmet, as shown and described.

DESCRIPTION

FIG. 1 is a front, top and left perspective view of a video camera housing for football helmet showing our new design; FIG. 2 is a front elevational view thereof; FIG. 3 is a right side elevational view thereof; FIG. 4 is a top plan view thereof; and, FIG. 5 is a bottom plan view thereof.

The broken lines in the drawings show environmental structure and form no part of the claimed design.
